INSOLE AND METHOD OF MAKING THE SAME

Harry E. Wagner, Endicott, N. Y., assignor to
United Shoe Machinery Corporation, Paterson,
N. J., a corporation of New Jersey

Application December 1, 1936, Serial No. 113,627

9 Claims. (Cl. 12—146)

This invention relates to insoles, particularly to insoles provided with sewing lips or ribs such as are used in the manufacture of Goodyear welt shoes, and to methods for use in the manufacture 5 of such insoles.

Objects of the invention are to provide an insole which is economical to manufacture, which possesses the requisite strength and which has the desired degree of flexibility.

10 In the practice of my improved method of making insoles as herein illustrated, a suitable piece of material, for example leather, is cut or rounded into the shape of a last bottom and is provided with either an inside or an outside channel. The marginal portion of the outer face of 15 the insole is coated with cement, preferably cement which is pressure responsive, and the cement allowed to dry. A tape, preferably coated on both sides with pressure-responsive cement, 20 has its central portion folded over a core or upon itself and the marginal portions of the tape turned outwardly with respect to the folded portion and caused to adhere to the cement on the marginal portion of the insole body, the folded portion of the tape being located in a plane substantially perpendicular to the insole body and substantially in alignment with the bottom of the channel formed therein. The lip of the channel is then raised and pressed against the 25 upstanding folded portion of the tape, the marginal portion of the tape which adheres to the channel flap being thus turned up and enclosed between the folded portion and the insole lip.

The invention includes the novel insole construction produced by the practice of the described method.

These and other features of the invention will appear more fully from the following description when read in connection with the accompanying 40 drawing and will be pointed out in the appended claims.

In the drawing,

Fig. 1 is a perspective view of an insole body suitably rounded and channeled with an outside channel and cemented on the marginal portion 45 of its outer face;

Fig. 2 is an enlarged fragmentary section taken on the line II—II of Fig. 1;

Fig. 3 is a perspective view similar to Fig. 1 showing the insole after the folded tape has been applied thereto;

Fig. 4 is an enlarged fragmentary section of Fig. 3 taken on the line IV—IV;

Fig. 5 is a perspective view similar to Fig. 3 showing the insole after the outside lip has been

raised and pressed against the folded portion of the tape;

Fig. 6 is an enlarged fragmentary section taken on the line VI—VI of Fig. 5;

Fig. 7 is an enlarged fragmentary section of a modified form in which the core has been omitted and the tape folded upon itself;

Fig. 8 is a view similar to Fig. 7 and showing a usual reinforcement applied to the insole;

Fig. 9 is an enlarged fragmentary section showing a modified form of the invention in which the insole body is provided with an inside channel instead of an outside channel; and

Fig. 10 is similar to Fig. 9 and shows the inside channel flap and the inner flange of the 15 tape turned up against the inner face of the folded portion of the tape.

In making my improved insole by the illustrated novel method, a piece of material such as leather, which may be considerably thinner than that usually employed for lipped insoles, for example three irons in thickness, is rounded in a usual manner to form an insole 10 fitting the bottom of the last. The insole 10 may then be provided in the usual manner with an outside channel 12 extending inwardly from the edge face of the insole sufficiently to provide the usual width of feather when the channel flap 14 is turned up. The channeling may be done quite close to the outer face of the insole, a channel flap having the thickness of as little as one iron having been found satisfactory under some conditions. Either before or after the channeling operation the marginal portion of the outer face of the insole may be provided with a coating 16 of cement, a pressure-responsive cement such as latex or polymerized chloroprene being preferred. A strip or tape 18 of suitable textile material is coated with the same cement on both sides and allowed to dry. The tape 18 may then, as shown in Fig. 3, have its central portion folded over a core 20 forming a crease at the top edge of the core and the marginal portions 22, 24 turned outwardly relatively to the central folded portion and pressed against the cemented area 16 of the insole 10, the folded portion of the strip 18 being aligned substantially with the bottom of the channel 12. The cemented surfaces of the outturned portions 22, 24 readily adhere to the cemented surface 16 upon application of pressure and are permanently attached to the body portion 10.

The lip 14 is next turned up against the upstanding lip formed by the folded portion of the tape by a usual lip-turning machine and in this operation the marginal portion 22, which pref-

erably does not extend to the edge of the insole, is also turned up against the folded portion, the crease of the fold being at the base of the lip 14. Thus, as shown in Fig. 6, the insole 10 is 5 provided with a rib consisting of a layer of material 14 like that of the insole body, for example leather, and three layers of fabric at the portion of the rib next to the insole and two layers of fabric near the top of the rib of the insole. In this way a strong rib firmly attached to the insole is provided, part of the rib being integral with the body portion of the insole. Also, at the base of the rib where the 10 inseam stitches are inserted a greater thickness 15 of material is provided than in the outer portions of the rib which do not need it, these portions being subsequently trimmed off. An insole prepared in the manner described may, if desired, be further strengthened by applying 20 thereto the usual reinforcement of Gem duck or similar material. If desired, the core 20 may be omitted and the strip 18 folded upon itself, as shown in Fig. 7. The use of a core, however, stiffens the rib and assists in forming an even 25 and satisfactory fold in the tape. The core may be made of a strip of stiff paper folded into suitable shape. This form of insole may be reinforced with Gem duck or similar material, as shown at 26 in Fig. 8.

30 The insole thus made has on its feather, that is on the marginal portion of the insole over which the upper is lasted, and on its shoulder, that is on the outer face of the lip against which the upper is forced by the upper-wiping operations, split leather surfaces which are desirable 35 and facilitate the operation of lasting the upper.

Under some conditions it may be found advantageous to provide a split leather surface on the inner face of the rib to facilitate the movement 40 of the shoe with respect to a channel guide or anvil such as are characteristic of sewing and lasting machines. In this case, as shown in Fig. 9, the insole may be provided with an inside lip 30. The other steps of the method may then be 45 carried out substantially as above indicated, the final operation being the folding of the inside lip up against the inner face of the folded portion of the strip 18, as shown in Fig. 10. In this case it will be seen that the feather of the insole is formed, at least partly, by the outturned portion 22 of the tape and that the inner portion 50 of the tape is turned up against the folded portion with the inside lip 30.

Having thus described my invention, what I 55 claim as new and desire to secure by Letters Patent of the United States is:

1. That improvement in methods of making insoles which consists in channeling an insole-shaped body portion, folding the middle portion of a tape, turning the marginal portions of the tape outwardly with respect to the folded portion to dispose them in a plane perpendicular to the folded portion, cementing the marginal portions of the tape to the insole body with the folded portion substantially in alignment with the bottom of the channel, and turning the channel flap and one of the marginal portions of the tape up against the folded portion.
2. An insole comprising a body portion having 70 a channel lip disposed perpendicular to the body portion, said lip being reinforced on one face with three thicknesses of textile material formed by twice folding upon itself a single strip, the crease of one fold being located on top of the lip and the crease of the other fold at the

bottom of the lip, one marginal portion of the strip being secured flatwise to the body of the insole.

3. That improvement in methods of making insoles which consists in forming in the edge face of an insole-shaped body portion a channel substantially parallel to the surface of the insole, folding the central portion of a tape over a core, disposing the marginal portions of the tape outwardly with respect to the core, cement-attaching the marginal portions of the tape to the insole body with the core substantially in alignment with the bottom of the channel, and then turning the channel flap and the outer margin of the tape up against the outer face of the 15 folded portion.

4. That improvement in methods of making insoles which consists in forming an outside channel in an insole-shaped body portion, folding the middle portion of a tape, disposing the marginal 20 portions of the tape in opposite directions in a plane perpendicular to the folded portion, cementing the marginal portions of the tape to the insole body with the folded portion substantially in alignment with the bottom of the channel, and turning the channel flap and the outer marginal portion of the tape up against the outer face of the folded portion.

5. An insole comprising a body portion having an outside channel lip disposed perpendicular to 30 the body portion, said lip being reinforced on its inner face with three thicknesses of textile material formed by twice folding a single strip, the crease of one fold being located on top of the lip and the crease of the other folded at the 35 bottom of the lip, the inner portion of the strip being secured flatwise to the body of the insole.

6. That improvement in methods of making insoles which consists in channeling an insole-shaped body portion a predetermined distance inwardly from its edge face and parallel to and adjacent to its outer face, applying pressure-responsive cement to the marginal portion of the outer face of the insole, providing a tape coated with similar cement on both sides, folding the 40 central portion of the tape over a core, pressing oppositely directed marginal portions of the tape against the cemented area of the margin of the insole with the core perpendicular to the insole and with one edge thereof substantially aligned with the bottom of the channel, then turning up the channel flap and the outer margin of the tape against the cement-coated outer surface of the folded portion and thereby causing the marginal portion and the channel flap to be adhesively secured to the outer side of the folded portion.

7. That improvement in methods of making insoles which consists in forming in the edge face of an insole-shaped body portion an inside channel parallel to the surface of the insole, folding the central portion of a tape over a core, disposing the marginal portions of the tape in opposite directions, cement-attaching the marginal portions of the tape to the insole body with one edge of the core substantially in alignment with the bottom of the channel, and then turning the channel flap and the inner marginal portion of the tape up against the inner face of the folded portion.

8. An insole comprising a body portion having 70 an inside channel lip disposed perpendicular to the body portion, said lip being reinforced on its outer face with three thicknesses of textile material formed by twice folding a single strip, the crease of one fold being located on top of the

the lip and the crease of the other fold at the bottom of the lip, the outer portion of the strip being secured flatwise to the body of the insole.

9. That improvement in methods of making insoles which consists in forming an inside channel in an insole-shaped body portion a predetermined distance inwardly from its edge face and substantially parallel to and adjacent to its outer face, applying pressure-responsive cement to the 10 marginal portion of the outer face of the insole including the channel flap, providing a tape coated with similar cement on both sides, folding the central portion of the tape, oppositely disposing

the marginal portions of the tape, pressing the marginal portions of the tape against the cemented area of the marginal portion of the insole with the lower edge of the folded portion thereof substantially aligned with the bottom of the channel, 5 then turning up the channel flap and the outer margin of the tape against the cement-coated inner surface of the folded portion and thereby causing the marginal portion and the channel flap to be adhesively secured to the inner side of 10 the folded portion.

HARRY E. WAGNER.
